GARMENT HANGER STEM

Carl E. Gingher, 304-328 Depot St.,
Scranton, Pa. 18509

Filed Dec. 9, 1968, Ser. No. 14,854

Term of patent 14 years

Int. Cl. D6—07

U.S. Cl. D80—8

FIG. 1

FIG. 2

FIG. 3

FIG. 4

FIG. 1 is a perspective view of a garment hanger stem embodying my new design;

FIG. 2 is a side elevational view thereof;

FIG. 3 is an end elevational view thereof; and

FIG. 4 is a top plan view thereof.

I claim:

The ornamental design for a garment hanger stem, as shown.
